[57] CLAIM

The ornamental design for an accessory housing for
skate, skateboard, bicycle or the like, as shown and
described.

DESCRIPTION

FIG. 1 is a front elevational view of the accessory housing
for skate, skateboard, bicycle or the like forming our
new design;

FIG. 2 is a rear elevational view thereof;

FIG. 3 is an elevational view of one end thereof;

FIG. 4 is an elevational view of the opposite end
thereof;

FIG. 5 is a top plan view thereof; and

FIG. 6 is a bottom plan view thereof.

FIG. 1

FIG. 2
